UNITED STATES PATENT OFFICE.

CHARLES A. McNEAL, OF NEWARK, OHIO.

INTERCHANGEABLE-LETTER SIGN.

1,189,461.

Specification of Letters Patent.

Patented July 4, 1916.

Application filed November 30, 1915. Serial No. 64,309.

To all whom it may concern:

Be it known that I, CHARLES A. McNEAL, citizen of the United States, resident of Newark, in the county of Licking and State 5 of Ohio, have made a certain new and useful Invention in Interchangeable-Letter Signs; and I do declare the following to be a full, clear, and exact description of the same, such as will enable others skilled in the art to 10 which it appertains to make and use the invention, reference being had to the accompanying drawings, and to letters or figures of reference marked thereon, which form a part of this specification.

15 Figure 1 is a front view of the invention partly broken away. Fig. 2 is a plan view of the same. Fig. 3 is a section on the line 3—3 Fig. 1. Fig. 4 is a perspective view of the end section and one letter section or 20 panel, the key member being shown as partly removed.

The invention has relation to illuminated signs having interchangeable letters, having 25 for its object to provide an improved sign wherein the reading matter may be quickly set up and quickly changed, the joints between the letters being light proof and the letter panels being securely locked to each other and to the frame of the sign.

30 The invention consists in the novel construction and combinations of parts, as hereinafter set forth.

In the accompanying drawings, illustrating 35 the invention, the numeral 2 designates the sign box or frame, having suitable means of interior illumination and provided with a continuous unobstructed opening 3 extending longitudinally thereof. At the sides of this opening, being at top and bottom thereof in 40 a horizontal sign, the frame is provided with longitudinal grooves 4, 4, usually through the medium of outwardly extending top and bottom strips 5, 5, having respectively at their outer ends upturned and downturned flanges 5', 5'.

45 6, 6 designate the letter panels, which are provided each at the outer side with lateral or vertical flanges 7, 7, directed toward each other, and upon the reverse side with top 50 and bottom horizontal flanges 8, 8, directed respectively downward and upward. The letter panels are slid into engagement with the flanges of the frame, to cover the opening thereof, from either end of said opening, 55 one after another, to make the word or words desired, the top and bottom flanges of the

letter panel engaging the oppositely directed top and bottom flanges of the frame.

The panels are connected together in chain fashion by tie or key members 9, 9, each of 60 which is provided upon the reverse side with vertical inturned flanges 10, 10, extending toward each other and engaging the oppositely directed outer flanges of adjacent panels, in a light tight manner, the engagement of the letter panels with the flanges of the frame being similarly light tight. The tie members serve to lock the line of letters together, and each said member is provided with a stop lug 11, engaging the letter panel 65 to limit the sliding movement of the key.

At each end of a line of letters end plates 12, 12 are provided, each of which has a lateral or vertical flange 13 directed toward the end of the frame, the endmost tie member 75 having engagement with this flange and with the oppositely directed flange of the endmost letter panel. The end plates have each a right-angle flange 14, covering the end of the longitudinal opening of the frame. 80

Blank panels are provided for spacing when needed.

The sign is designed to be quickly assembled, dismantled and reassembled, and there being no electrical connections required in 85 setting up the reading matter, skilled labor is dispensed with.

I claim:

1. In an interchangeable letter sign, a frame having a longitudinal guideway, and 90 a chain composed of aligned letter panels and of removable transverse slidable tie means separate from and locking said panels together, said chain sliding as a whole in said guideway.

95 2. In an interchangeable letter sign, a frame having a longitudinal opening provided with an open-end guideway bounding said opening, and a chain composed of aligned letter panels and of removable transverse 100 slidable tie means located at the joints of and separate from and locking said panels together, said chain slidable as a whole in said guideway.

3. In an interchangeable letter sign, a frame having a longitudinal guideway, and a chain composed of aligned letter panels having flanges and of removable transverse 105 slidable tie means having flanges engaging the flanges and located at the joints of the 110 panels, said chain slidable as a whole in said guideway.

4. In an interchangeable letter sign, a frame having a longitudinal guideway, and a chain composed of aligned letter panels having outer undercut flanges and of removable transverse slidable tie means having upon the reverse side undercut flanges engaging the flanges and located at the joints of the panels, said chain slidable as a whole in said guideway.
5. In an interchangeable letter sign, a series of aligned letter panels having outward projecting flanges, and sliding tie members having inward projecting flanges embracing and locking the flanges of said panels together into a composite whole.
6. In an interchangeable letter sign, a frame having a longitudinal opening and undercut flanges bounding said opening, a series of aligned letter panels having upon the reverse side undercut flanges engaging the flanges of said frame and upon the outer side undercut flanges, and tie members having upon the reverse side undercut flanges engaging the flanges of said panels.
7. In an interchangeable letter sign, a frame having a longitudinal opening and undercut flanges bounding said opening, a series of aligned letter panels and end panels having upon the reverse side undercut flanges engaging the flanges of said frame and upon the outer side undercut flanges, and tie members having upon the reverse side undercut flanges engaging the outer flanges of said panels, said end panels having flanges covering in the ends of said openings.

In testimony whereof I affix my signature in presence of two witnesses.

C. A. McNEAL.
